UNITED STATES PATENT OFFICE.

M JAY SAGE, OF BROOKLYN, NEW YORK.

FILL-BOX FOR STORAGE-TANKS.

1,317,595.

Specification of Letters Patent. Patented Sept. 30, 1919.

Application filed January 30, 1918. Serial No. 214,561. Renewed May 9, 1919. Serial No. 291,924.

To all whom it may concern:

Be it known that I, M JAY SAGE, a citizen of the United States, and a resident of the city of New York, borough of Brooklyn, in the county of Kings and State of New York, have invented a new and Improved Fill-Box for Storage-Tanks, of which the following is a full, clear, and exact description.

10 My invention relates to boxes placed on street corners to give access to the storage tanks, such as are provided underground in gasoline stations.

15 An object of the invention is to provide a simple and convenient box which is provided with a strainer through which the fluid is caused to pass before it can enter the storage tank.

20 Another object of the invention is to provide a box in which the access to deliver liquid to the strainer and the access to the strainer are controlled independently.

25 With the above and other objects in view, the nature of which will more fully appear as the description proceeds, the invention consists in the novel construction, combination and arrangement of parts as herein fully described, illustrated and claimed.

30 In the accompanying drawings, forming parts of the application, similar characters of reference indicate corresponding parts in both views.

35 Figure 1 is a top plan view of the box as it appears closed, a portion of the cover being broken out to show the details of construction; and

Fig. 2, a vertical section on line 2—2, Fig. 1.

40 Referring to the drawings, 3 is the box which has at the bottom a depending well 4 disposed centrally with the box and which presents a threaded portion 5 above the bottom of the box. A cap 6 has a threaded engagement with the threaded portion 5 and 45 forms a cover for said well 4. The cap 6 also serves as a retainer for a strainer 7 which is in the form of a cylindrical member having a flange 8 at the top which rests on a shoulder 9 provided in the well 4 near 50 the top of same so that the strainer is suspended within the well 4 from said shoulder 9. The bottom 10 of the strainer 7 is preferably solid so that the bottom cannot be injured when a rod is inserted into the 55 strainer through the threaded plug 11 in

the cap. Through this plug the conduit for delivering liquid to the storage tank is introduced into the strainer.

The plug 11 has a lug 12 rising from the top of the plug and which is engageable by a latch 13 pivotally connected to ears 14 projecting from the side wall of the box 3. The lug 12 is provided with an opening 15 through which a padlock 16 may be passed and locked when the latch is in engagement 60 with the lug and whereby the plug 11 is prevented from being removed from the cap by an unauthorized person. This arrangement prevents the addition of water or theft of the gasoline from the storage tank 70 through the conduit leading from the box to the storage tank.

On the other hand, it is desirable to prevent the man who discharges the liquid into the storage tank from having access to the 75 strainer, for in his desire to quickly discharge the contents he would remove the strainer and discharge the liquid directly into the tank, thereby allowing dirt or impurities present in the liquid to enter the 80 storage tank, which is very undesirable. For this reason I provide the cap 6 with lugs 17 formed on the margin of the cap. These lugs are preferably diametrically opposite and are adapted to be engaged by a latch 18 85 pivotally connected to ears 19 provided on the wall facing the wall to which the latch 13 is secured. The lug 17 proximate to the latch 18 will project through the latch 18 so that a padlock 20 could be secured 90 thereto. To prevent interference between the lug 17 which is proximate the latch 13 an opening 21 is provided therein for said lug.

95 This arrangement allows the removal of the strainer only when the two padlocks 16 and 20 are removed. In other words, if the strainer 7 becomes clogged the person filling the tank can request the man who has the key to the other padlock, which will be the 100 owner of the tank into which delivery is made, to permit him to remove the strainer to clean the same. The owner, under no circumstances, can have access to the filling plug, as the same is controlled by the person who controls the delivery, thereby 105 adulteration of the product delivered by the owner is prevented. The box has a cover 22 which can be locked to the box by a tongue 23 provided on the under side of the 110

cover and operable from the top of same by means of a suitable angular key, as common in an arrangement of this character.

I claim:

- 5 1. In a fill box, a well, a cap for the well, a latch associated with the box and adapted to engage the cap so as to prevent the rotation of said cap, a filling plug in the cap, and a latch associated with the box for engaging the filling plug so as to prevent the rotation of same.
- 10 2. In a fill box, a well, a cap for the well, a latch associated with the box adapted to engage the cap whereby the cap is locked to the well, a filling plug in said cap, and a latch for engaging the filling plug and preventing the removal of same.
- 15 3. In a fill box, a well, a cap for locking said well, a lug on said cap, a latch in the box for engaging the lug, said lug having means for receiving a padlock, a filling plug in said cap, a lug on said filling cap,

and a latch in the box for engaging the lug of the filling plug, said lug having means for receiving a padlock.

4. In a fill box, a well, a cap threaded to the well for locking the well, a lug on said cap, a latch hinged to the wall of the box and adapted to engage the lug, said lug having means for receiving a padlock, a filling plug threaded into the cap, a lug on said filling cap, a latch hinged to a wall of the box and adapted to engage the lug of the filling plug, said filling plug having means for receiving a padlock.

30 5. In a fill box, a well, a closing cap threaded to the well, a filling plug threaded into the cap, said filling plug and cap having lugs, and latches hinged to the box and adapted to engage the lugs, said lugs having means whereby a padlock may be attached thereto.

40 M JAY SAGE.
